United States Patent Office.

ANDREW MURRAY, OF LOWELL, MASSACHUSETTS, ASSIGNOR TO
LOWELL MANUFACTURING COMPANY, OF SAME PLACE.

Letters Patent No. 89,065, dated April 20, 1869.

IMPROVEMENT IN POWER-LOOM FOR WEAVING INGRAIN-CARPETS.

The Schedule referred to in these Letters Patent and making part of the same.

Be it known that I, ANDREW MURRAY, of Lowell, in the county of Middlesex, and State of Massachusetts, have invented certain new and useful Improvements in Ingrain-Carpet Power-Looms; and I do hereby declare that the following is a full, clear, and exact description of the construction and operation of the same, reference being had to the annexed drawings, making a part of this specification, in which—

Figure 1 is a front elevation of my improvements, and such other parts of the loom as are necessary to exemplify them;

Figure 2, an end elevation of the same; and

Figure 3, a horizontal section taken on the red line A B in fig. 2.

Figure 4 represents my invention in a modified form.

Ingrain-carpet power-looms, which operate a double series of shuttles, have their shuttle-boxes detached from the lay, and supported by pendulous frames, there being one such frame at each side of the loom.

To bring the two series of shuttle-boxes into alternate action, the pendulous frames are caused to vibrate, and to swing to or fro during the time the lay beats up the cloth, and the shuttles are at rest.

The pendulous frames, with their shuttle-boxes, are necessarily heavy, and to move them in quick succession, and bring them to a stationary position, in a proper line with the reed, for the passage of the shuttles, without shock or jarring of the mechanism, is of much importance to the successful working of the loom.

The mode of vibrating the pendulous frames, heretofore practised, is described in a patent for improvements in power-looms for weaving ingrain-carpets, granted to E. B. Bigelow, February 18, 1846, and re-issued September 25, 1849.

By the mode just referred to, motion is transmitted from a cam to the pendulous frames, through an oscillating shaft, which extends across the loom from side to side, and operates two oscillating crank-shafts, with cranks carrying rollers, which ply in slots formed in the frames, or in stands affixed to the frames, the crank-arms being half the length of the motion to be imparted, so that by turning the crank-shafts half a revolution in either direction, they will severally vibrate the frames accordingly.

An objection to this mode of connecting the pendulous frames with the cam which operates them, arises from the looseness of the connections, and the consequent backlash and jarring of the frames when the loom is suddenly stopped while the frames are in motion.

To obviate this objection is the object of my invention, a part of which consists in connecting the pendulous frames with the cam or cams which actuate them, by vibrating connecting-bars, which are pivoted or hinge-jointed to the pendulous frames, and vibrate endwise in the direction in which they swing, whereby the motion imparted by the cam or cams is transmitted

to the pendulous frames more directly and steadily than has heretofore been done.

This part of my invention may be used with devices for operating both of the pendulous frames by one cam, or with devices for operating each pendulous frame by a special cam.

Another part of my invention consists in combining a cam with each of the pendulous frames, whereby the connections between the moving-power and the pendulous frames are more direct and steady than when both frames are actuated by one cam, as heretofore practised.

And another part of my invention consists in uniting and vibrating the two pendulous frames by a revolving shaft, which extends across the loom from side to side, and carries two cams, by which the pendulous frames are severally actuated, the vibratory action of the cams being communicated to them by vibrating connecting-bars, as before explained.

By reference to the annexed drawings, the character and operation of my invention will now be readily understood.

The loom-frame is marked *a*.

The pendulous frames which support the double series of shuttle-boxes, are marked *b*.

Each frame has one of the series of shuttle-boxes, *c*, represented in connection with it, but it was deemed unnecessary to represent the other series, as the mode of constructing and arranging the double series is well understood.

The pendulous frames *b* are suspended from and vibrate on axes *d*, which may be supported by the loom-frame, or by beams connected with the mill-building.

To the pendulous frames *b*, near their lower ends, vibrating connecting-bars *e* are pivoted or hinge-jointed, the pivots or hinge-joints being marked *f*.

The rear ends of the vibrating connecting-bars *e* are bent and bolted together, as shown in fig. 3.

They are also provided with slots, *g*, which receive a revolving shaft, *h*, on which they slide, and by which they are guided and supported.

The revolving shaft *h* extends across the loom from side to side, and is supported by bearings *i*.

In looms for weaving two-ply carpets, it is caused to revolve once to every two revolutions of the lay-shaft, and in three-ply looms, once to every three revolutions of the lay-shaft.

It carries two cams, marked *j*, one for each of the pendulous frames, which cams act on friction-rollers *k*, and impart a vibratory movement to the vibrating connecting-bars *e*, which vibratory movement is communicated to the pendulous frames *b* by the vibrating connecting-bars *e*, with which they are respectively connected.

The cams *j* are adjusted on the shaft *h*, so as to bring their eccentric sides on opposite sides of the

shaft, by which means they cause the pendulous frames to swing simultaneously in opposite directions.

In weaving some kinds of carpets, however, it is desirable to have the pendulous frames swing in unison, and in such cases the eccentric part of both the cams is placed on the same side of the shaft.

It will be obvious to persons acquainted with the construction of machinery, that the form and arrangement of the parts which compose my invention, may be varied without departing from its distinguishing features. As, for instance, instead of having a single-faced cam to vibrate the pendulous frames, acting on one roller, to move them forward, and on another to draw them back, as represented in the drawings, a grooved cam may be used, having one roller plying in its groove, which receives both the forward and backward actions of the cam.

Fig. 4 represents, also, a mode in which the form and arrangement of the parts which transmit the vibratory action of the cam to the pendulous frames may be varied.

An oscillating shaft, *l*, there being one such shaft at each side of the loom, carries two upright arms, *m*, which are connected with the pendulous frames *b* by the vibrating connecting-bars *e*, pivoted or hinge-jointed thereto.

The shaft *l* also has another arm affixed to it, which carries a roller, *k*.

A grooved cam, *j*, on the shaft *h*, acts on the roller *k*, and imparts a vibratory motion to the vibrating con-

necting-bars *e*, which communicate the same motion to the pendulous frames, with which they are severally connected.

Having thus fully described my invention, and pointed out some of the modifications of which it is susceptible, without departing from its distinguishing principles,

What I claim, and desire to secure by Letters Patent, is—

The combination of the vibrating connecting-bars with the pendulous frames, herein described, when said vibrating connecting-bars are pivoted or hinge-jointed to the pendulous frames, and communicate thereto the vibratory action of a cam or cams, substantially as specified.

I also claim, in combination with each of the pendulous frames, a cam, by which said pendulous frames are severally operated, substantially as described.

I also claim the combination of mechanism herein described, for uniting and vibrating the two pendulous frames, consisting of a revolving shaft, extending across the loom from side to side, two cams, carried by said shaft, and vibrating connecting-bars, which severally communicate the vibratory action of said cams to the pendulous frames, substantially as specified.

ANDREW MURRAY.
